US00D966389S

(12) **United States Design Patent** (10) **Patent No.:** **US D966,389 S**
(45) **Date of Patent:** **** Oct. 11, 2022**

(54) **VIDEO CAMERA**

(71) Applicant: **SHENZHEN OIKAY INNOVATION TECHNOLOGY CO., LTD.**, Shenzhen (CN)

(72) Inventor: **Yang Xu**, Shenzhen (CN)

(73) Assignee: **SHENZHEN OIKAY INNOVATION TECHNOLOGY CO., LTD.**, Shenzhen (CN)

(**) Term: **15 Years**

(21) Appl. No.: **29/815,630**

(22) Filed: **Nov. 15, 2021**

(51) LOC (13) Cl. **16-01**

(52) U.S. Cl.

USPC **D16/202**

(58) **Field of Classification Search**

(57) **CLAIM**

The ornamental design for a video camera, as shown and described.

DESCRIPTION

FIG. 1 is a perspective view of a video camera showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines in the drawings depict portions of the video camera that form no part of the claimed design.

1 Claim, 8 Drawing Sheets
